Patented Feb. 20, 1917.

INVENTOR:
George Walker Gilmer,
By Chas. J. Parker,
Attorney.

UNITED STATES PATENT OFFICE.

GEORGE WALKER GILMER, JR., OF PHILADELPHIA, PENNSYLVANIA, ASSIGNOR TO
L. H. GILMER COMPANY, OF PHILADELPHIA, PENNSYLVANIA, A CORPORATION OF
NEW JERSEY.

BELT.

1,216,437

Specification of Letters Patent. Patented Feb. 20, 1917.

Application filed May 6, 1916. Serial No. 95,756.

To all whom it may concern:

Be it known that I, GEORGE WALKER GILMER, JR., a citizen of the United States, residing in the City of Philadelphia, county of Philadelphia, and State of Pennsylvania, have invented certain Improvements in Belts, of which the following is a specification.

This invention relates to belts for transmitting power and its primary object is to provide an efficient endless laminated construction of substantially uniform strength and thickness, strong and durable character, and simple and inexpensive construction.

15 The characteristic improvements of my invention are fully disclosed in the following description and the accompanying drawings in illustration thereof.

In the drawings, Figure 1 is a perspective 20 view of an initial form in the manufacture of the belt, in which a section of webbing has been wound in a two-ply loop connected by longitudinal stitching, with free overlapping ends separated by a continuous 25 part of the section; Fig. 2 is an enlarged perspective view of a part of the construction shown in Fig. 1 with the filling thread raveled out of the overlapping ends; Fig. 3 is a view similar to that shown in Fig. 2 with the further development that substantially half of the loose warp ends have 30 been trimmed out; Fig. 4 is a view similar to that shown in Fig. 3 with the further development that the butts of the inner and outer unraveled ends have been sewed down 35 to the intermediate body part of the belt by several rows of transverse stitching and the ends remaining free have been feathered or reduced gradually from the stitching to 40 their termini; Fig. 5 is a view similar to that shown in Fig. 4 with the further development that the loose warp ends have been sewed down by transverse stitching after having been feathered or thinned in 45 a wedge-like form so that such reversely tapered ends together have cross-sections approximately equal to those of the unreduced warp; and Fig. 6 is a perspective view of the finished belt with the ends and body 50 connected by transverse and longitudinal stitching.

As illustrated in the drawings, webbing of the desired character is wound to form

a loop comprising laminations 1 and 1' of a desired ply and the section of webbing required for the belt is so cut that the inner end 1^a and the outer end 1^b overlap with the part 1'' of the body of the section between them. The plies or laminæ 1 and 1' are connected between the ends 1^a and 1^b by the longitudinal stitching 2 so that such laminæ are held in smooth closely conforming relation with avoidance of the tension in the outer strata, and the compression in the inner strata that is developed by making small belts in one ply form.

The free ends 1^a and 1^b now have the weft or filling threads raveled out to approximately the extent they overlap, as illustrated in Fig. 2; then approximately 70 half of the free warp ends 1^c and 1^d are cut out adjacent to the part 1'', as illustrated in Fig. 3, and this is followed by forming the stitches 3 and 3' across the butts of the loose warp ends through the part 1'' of the webbing which joins a part 1 to a part 1', as illustrated in Fig. 4, free ends of each warp being thrown back in stitching down the others to prevent such free ends being caught by the stitching. 80

The warp ends left free after the cross-stitching 3 and 3' are now feathered or thinned down toward their termini after the form of oppositely disposed wedges so that the resulting overlapping ends 1^e and 1^f together are approximately equal in their cross-sections to cross-sections of a single ply of the webbing, and the parts 1'', 1' and 1' have together approximately the strength of two parts 1 and 1'. 90

The feathered ends 1^e and 1^f are now secured throughout their lengths to the part 1'' by first cross-stitching 4, as illustrated in Fig. 5, and then by the longitudinal stitching 5, as illustrated in Fig. 6, the latter showing the completed belt. 95

It will be understood that while I have illustrated and described the best method and construction known to me for general use, the details may be variously modified at the convenience of the manufacturer, by reason of the character of the material used and for products having special characteristics.

Having described my invention, I claim: 105

1. A belt comprising a single piece of

webbing wound to provide a laminated portion and having feathered ends separated by an intermediate part of the webbing and means for securing said part and ends together.

2. A belt comprising a laminated loop of webbing having overlapping ends of warp threads from which the weft threads have been removed and means for securing said ends to an intermediate part of the loop of said webbing.

3. A belt comprising a section of webbing wound to provide a loop having several plies and overlapping raveled warp ends of reduced cross section sewed to an intermediate part of the webbing.

4. A belt comprising a section of webbing wound to provide a loop having several plies connected by longitudinal stitching

and feathered warp ends sewed to an intermediate part of the webbing. 20

5. A belt comprising a section of webbing wound to provide a loop having several plies with reduced overlapping warp ends from which the weft has been removed and 25 stitching including seams across said warp ends for securing them to an intermediate part of the webbing.

6. A device of woven material having thinned and feathered overlapping warp 30 ends from which the weft threads have been removed and having an intermediate layer to which said ends are sewed by stitching including seams across and through said ends and intermediate layer. 35

In testimony whereof I have hereunto set my name this 29th day of April, 1916.

G. WALKER GILMER, JR.
